CROSS-ROLL

Samuel E. Diescher, Pittsburgh, Pa., assignor to
 Diescher Tube Mills, Inc., Pittsburgh, Pa., a
 corporation of Delaware

Application May 24, 1933, Serial No. 672,585

8 Claims. (CL. 80—13)

My invention relates to apparatus for treating cylindrical work-pieces by helically acting cross-rolls and particularly to means for assisting the delivery of the products of such cross-roll apparatus therefrom and for regulating the diameters of the products thereof.

In the operation of cross-roll apparatus having helically acting rolls, difficulty sometimes occurs in effecting delivery of the treated product. This is particularly true in the operation of cross-rolling piercing mills. As the trailing end of the work-piece passes between the cross-rolls, the extent of surface contact between the rolls and the work-piece becomes progressively less and the force exerted by the cross-rolls on the billet is correspondingly reduced and may, before the work-piece is delivered from between the cross-rolls, become too weak to overcome the friction of the commonly used fixed guides, or, in a piercing mill, to draw the trailing end of the billet over the mandrel point.

For the purpose of overcoming this difficulty, and for the further purpose of accurately regulating the outside diameter of the pierced billets, piercing mills having cross-rolls of generally cylindrical, or barrel, form have heretofore been provided with collars at the outlet end of the rolls for engaging the pierced billets as they advance from the rolls. These outlet collars operate on the billet in the same manner as the outlet surfaces of the rolls to rotate the billet and advance it helically, thus exerting a longitudinal pull on the billet supplemental to that exerted by the cross-rolls. Adjustment of these outlet collars for taking up wear or for varying the distance between their billet-engaging surfaces has been accomplished by tilting the roll shafts. Adjustment of the collars in this way is, however, impractical in a mill having conical rolls.

According to the present invention, outlet collars are provided on the rolls of cross-rolling piercing mills and other cross-rolling mills having mushroom-shaped or other conical rolls, and adjustment of the collars to vary the distance between their work-engaging surfaces or to take up wear is provided for by mounting the collars so as to be adjustable axially toward and from the respective rolls. Such axial adjustment of the collars gives the desired variation of the distance between the collars because of the roll axes being inclined to the line of feed of the work.

These outlet collars must, in order to engage the work-piece, be of greater diameter than the rolls with which they are associated, and the peripheral speed of the outlet collars will, there-

fore, be greater than that of the rolls when moving at the same angular speed. This would cause twisting of the work-piece unless the collars were positioned with relation to the rolls to bear so lightly on the work-piece as to slip thereon, and it would be impractical to depend upon such slip to avoid twisting of the work-piece. According to the invention, twisting of the work-piece by the action of the collars is avoided, or controlled as desired, by providing a frictional slip-permitting driving connection between each collar and the roll with which it is associated, so that the collar, while acting to apply a driving torque to the work-piece, may assume the same or substantially the same peripheral speed as the work-piece, the collars being thus frictionally driven to exert a limited torque on the work-piece.

My invention will be further described in connection with the accompanying drawing in which Fig. 1 is a view, partially in elevation and partially in section, of a pair of cooperating cross-rolls provided with collars of my invention, a partially pierced billet and a portion of a mandrel being shown in operative positions between the rolls; Fig. 2 is an enlarged longitudinal sectional view of a portion of one of the collars of Fig. 1; Fig. 3 is a transverse sectional view taken on line III—III of Fig. 1; and Fig. 4 is a transverse sectional view taken on line IV—IV of Fig. 1.

Referring to the drawing, two conical cross-rolls 1 and 2, which may be of the somewhat mushroom shape shown, or other suitable conical shape, are spaced apart to provide for the passage of work-pieces therethrough. The cross-rolls are mounted for operation in the usual manner with the axes of their shafts 3 inclined to each other and to the line of feed of work-pieces passing therebetween and skewed, that is, set at different angles to a plane containing the center line of feed of the work-pieces and containing or parallel to the shortest line between the rolls, so that a helical movement is imparted to the work-piece.

Each of the cross-rolls 1 and 2 has associated therewith at its outlet end an axially aligned collar 4 which rotates with the roll in engagement with the work-piece, and which in the construction shown, instead of being mounted on an extension of the roll, is carried by a disc 10 slidably keyed to the shaft 3 for rotation therewith and for axial movement thereon to adjust the collar 4 toward and away from the cross-roll. The discs are retained in their axial positions relative to the cross-rolls by means of tension bolts 5 extending through these members and spacing bolts 55

6. These bolts may be employed in any suitable manner, three of each being shown by way of example.

The spacing between the collars and the cross-rolls is maintained by the adjustable bolts 6 which extend through the discs 10 and into engagement with the outer ends of the cross-rolls. Each of the bolts 6 is provided with a polygonal head 7 by means of which it may be adjusted, and a lock nut 8 by means of which it may be secured in adjusted position. Adjustment of the discs and collars toward and from the respective cross-rolls varies the distance between the work-piece engaging surfaces of the collars.

15 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

mine the torque resistance under which the collar and sleeve will slip with respect to the disc 10. Ducts 21 and 22, having an outer closure 23, serve to convey any suitable lubricant to the friction surfaces.

Cross-rolls equipped with outlet collars according to my invention may be employed for piercing billets, as shown in Fig. 1. It may be assumed that the mandrel 26, a portion of which is shown in Fig. 1 is, as usual, restrained from longitudinal movement by any suitable means, such for example as a thrust bearing, not shown, for permitting rotation of the mandrel.

It may be assumed, also, that a billet 27 has entered the pass between the cross-rolls and has 15 been pierced substantially to the degree shown in Fig. 1. Thereafter, as the billet progresses to the left, as viewed in Fig. 1, and the trailing end thereof nears the throat or point of narrowest space between the cross-rolls, it presents a progressively smaller area for engagement by the cross-rolls, and, because of this small area of engagement, it may occur that the longitudinal force exerted by the cross-rolls alone upon the billet is not sufficient to force the trailing end of 20 the billet completely over the point of the mandrel to complete the piercing operation. However, the engaging surfaces of the collars 4, operating in the same manner as the outlet surfaces 20 of the cross-rolls, exert an additional longitudinal pull on the billet, and the piercing operation is by reason of this additional pull completed regardless of the sufficiency of the force exerted by the cross-rolls to accomplish the completion of 25 the piercing operation.

30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

In case the torque resistance on the collars 4 during the piercing operation exceeds the amount for which the frictional engagement of the grooves 11 and 18 is adjusted, slippage will occur between the disc 10 and the collars and sleeves 15 to permit the collars to drive the billet without, or substantially without, twisting it. The friction drive may be adjusted so that the collars will assume the same circumferential speed as that of the billet during actual piercing and 45 so long as the cross-rolls retain their strong grip on the billet, but that as the piercing finishes and the cross-rolls lose their grip on the billet, the peripheral speed of the collars will increase with decrease in the torque resistance as the billet is 50 released from the rolls. Danger of the trailing end of the billet not passing over the mandrel point is thus avoided and the pierced billet is delivered quickly from the mill.

In case of wear such as to reduce the diameter 55 of the engaging surfaces of the collars, suitable adjustment may be made by means of the bolts 5 and 6 to shorten the distances between the cross-rolls and the corresponding collars 4 to cause the latter to exert the desired pressure on the billet. 60

The frictional engagement between the grooves 11 and ribs 18 and between the walls of the recess 12 and flange 14 may be regulated by adjusting the bolts 20, whereby twisting of the walls of the work-pieces by the collars 4 may be substantially 65 eliminated or may be controlled as desired.

While cross-rolls provided with outlet collars in accordance with my invention have been illustrated and described as being employed in connection with the piercing of billets, it will be appreciated that the use of the collars is not necessarily limited thereto. The collars may be employed in connection with cross-rolling mills for wall thickness reduction and elongation of tubes and other cross-rolling mills in which it is desired 75

50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

to insure that the product of the mill is completely treated thereby and delivered therefrom after the completion of its operation, or for the purpose of varying and accurately delivering the diameters of products of the cross-rolling mills.

A further advantage from the use of the outlet collars is that the additional pull on the work-piece exerted by the collars has the effect of reducing the slippage between the work-piece and the rolls and thus increases the rate of forward movement of the work-piece.

I claim:

1. Cross-roll apparatus, comprising a pair of helically acting conical cross-rolls for treating work-pieces passing therebetween, means providing at the outlet end of each cross-roll a supporting surface concentric with the axis of the cross-roll, a collar of larger diameter than the cross-roll mounted on each such supporting surface to be frictionally driven to rotate with the cross-roll in engagement with the work-pieces, and means for adjusting the degree of frictional engagement by which the collar is driven to vary the torque resistance under which the collar will slip with relation to the cross-roll.

2. Cross-roll apparatus, comprising a pair of helically acting conical cross-rolls for treating work-pieces passing therebetween, an annular member mounted adjacent the outlet end of each cross-roll to rotate with the cross-roll in axial alignment therewith, a collar of larger diameter than the cross-roll mounted on each said annular member for engaging the work-pieces, and means providing friction driving connections between the collars and the annular members whereby the collars will be driven to rotate with the cross-rolls but will slip relatively to the annular members and cross-rolls under a predetermined torque resistance, said annular members being adjustable toward and from the respective cross-rolls to vary the distance between the work-piece-engaging surfaces of said collars.

3. Cross-roll apparatus, comprising a pair of helically acting conical cross-rolls for treating work-pieces passing therebetween, each of said cross-rolls being mounted on a shaft, a disc mounted for rotation therewith on each of said shafts adjacent the outlet end of the cross-roll and spaced therefrom and adjustable on the shaft toward and from the cross-roll, and a collar of larger diameter than the cross-roll mounted on each said disc for engaging the work-pieces, and means providing friction driving connections between the collars and the discs adjustable for varying the torque resistance under which the collars will slip on the discs.

4. Apparatus for piercing billets, comprising

helically acting conical cross-rolls for rolling a billet to advance it over a mandrel, a collar mounted at the outlet end of and in axial alignment with each of said cross-rolls to rotate therewith in engagement with the billet, said collars being adjustable toward and from the respective cross-rolls to vary the distance between the billet-engaging surfaces of the collars, and means for frictionally driving said collars to cause them to exert a limited torque on the billet.

5. Cross-roll apparatus, comprising a pair of helically acting cross-rolls for treating work-pieces passing therebetween, and a collar in axial alignment with each of said cross-rolls at the outlet end thereof means for positively driving the cross rolls and means for frictionally driving the collars, said collars being formed to engage and exert a limited torque upon a work-piece by reason of said frictional driving connection.

6. Cross-roll apparatus, comprising a pair of helically acting conical cross-rolls for treating work-pieces passing therebetween, each of said cross-rolls having at its outlet end in axial alignment therewith and adjustably spaced therefrom a collar of larger diameter than the cross-roll for engaging a work-piece, means for positively driving said cross rolls, and means for frictionally driving said collars whereby the collars exert a limited torque on a work-piece acted upon by the cross-rolls.

7. Cross-roll apparatus, comprising a pair of helically acting conical cross-rolls for treating work-pieces passing therebetween, each of said cross-rolls having at its outlet end in axial alignment therewith a collar of larger diameter than the cross-roll for engaging a work-piece, means for positively driving each cross-roll, means for frictionally driving its associated collar whereby permitting different relative angular speeds of rotation of said collars with respect to the cross rolls, the angular speed of rotation of the collar being less than that of its associated cross-roll to exert a limited torque upon a work-piece engaged by the cross-rolls.

8. Cross-roll apparatus, comprising a pair of helically acting cross-rolls for treating work pieces passing therebetween, a collar in axial alignment with each of said cross-rolls at the outlet end thereof, and a common driving means for driving each of said cross-rolls and its associated collar, means positively connecting said driving means to said cross-roll and means frictionally connecting said driving means to said collar, and said collars being formed to engage and exert a limited torque upon a work piece by reason of said frictional driving connection.

SAMUEL E. DIESCHER.
